UNITED STATES PATENT OFFICE.

WILLIAM C. M. SCHRADER, OF NEW YORK, N. Y.

CARBURETER-NOZZLE.

1,224,672.

Specification of Letters Patent.

Patented May 1, 1917.

Application filed March 29, 1915. Serial No. 17,951.

To all whom it may concern:

Be it known that I, WILLIAM C. M. SCHRADER, a native of Germany, having declared my intention of becoming a citizen of the United States, and a resident of the borough of Manhattan, city, county, and State of New York, have invented certain new and useful Improvements in Carbureter-Nozzles, of which the following is a specification.

Among the objects of my invention are, the attainment and utilization of the full efficiency of the liquid hydrocarbon fuel; smooth and uniform operation (by fuel feed) of motor under varying atmospheric conditions; obviation of carbon deposits; control of temperature of nozzle and fuel; perfect atomization of fuel; the use of moist air to increase oxidization; automatic regulation of feed to meet requirements, &c., all as hereinafter more fully set forth,—the invention consisting in the construction and arrangement of parts herein described and claimed specifically, whereby these results are attained.

In the accompanying drawings,

Figure 1, is a central longitudinal sectional elevation upon a greatly enlarged scale of a feed nozzle adapted to my method of feeding hydrocarbon fuel to motors, said nozzle being shown more or less diagrammatically for convenience of illustration;

Fig. 2, is a diagrammatic section showing means for effecting and regulating the supply of moist air to the feed nozzle;

Fig. 3, is a diagrammatic view illustrating means for supplying hot air to the feed nozzle.

Fig. 4 is a sectional and diagrammatic view showing the application of my improved nozzle.

In Fig. 1, *a*, designates the inlet for the supply of liquid hydro-carbon to the motor feed nozzle *A*, said inlet passage being preferably provided with a strainer *a'*, partitioning off the direct feed chamber *a''*, in which the rear end of the direct feed conduit *c*, is situated. The main body of the nozzle is lettered *b*, and is formed with a rear extension *b'*, to which the inlet conduit is secured by means of its disk shaped flange *a''*, formed with a peripheral screw thread *a'''*, for engagement with the female thread *b''*, on the extension *b'*.

The direct feed conduit *c*, consists of a central tube *c'*, and tubular sleeve or jacket

c'', secured thereto, said tubular sleeve *c''*, extending from the annular shoulder *c'''*, at the bottom of the central tube *c'*, to the annular shoulder *c''''*, on the under side of the conical valve head *c''''*, on the upper part of the central tube *c'*, which is also formed at its upper extremity with a spout extension *c''''*—the direct feed conduit *c*, extending axially from one extremity of the said central tube *c'*, to the other so as to afford direct communication between the feed chamber *a''*, and the ajutage chamber *d'*, which is countersunk in the head member *d*, secured to the body portion *b*, of the nozzle *A*. The inner side walls of the ajutage chamber *d'*, are conically convergent toward the valve port *d''*, and the chamber *d'* is inclosed at top by a partition *d''''*, formed with a central opening *d''''*, coincident with the spout *c''''*, of the direct feed conduct *c''*. The partition *d''''*, separates the ajutage chamber *d'* from the mixing chamber *e*, inclosed by the cap *e'*, and from which the fuel admixture is finally discharged into the combustion chamber of the motor through the screened aperture *e''*.

Between the central tube *c'*, and its sleeve *c''*, is formed a spiral duct or passage *c''''*, communicating at bottom with the axial feed chamber *a''* and at top with the valve chamber *f*, in which the conical valve *c''''*, is situated. The valve chamber *f*, communicates through one or more ducts *g'*, with the hydro-carbon reserve chamber *g*, which in turn communicates through the ducts *g''*, with the direct feed chamber *a''*, below.

H, is a hot air jacket, or compartment surrounding the body portion *b*, of the nozzle, and connected by a pipe or flue *h*, so arranged that the air will be heated by the exhaust pipe *h'*, of the motor. A purifier *b''*, is interposed in the conduit *h*, between the jacket *H*, and said exhaust, as indicated in Fig. 3. The hot air jacket *H*, communicates through ducts *h''*, with the hydro-carbon reserve chamber *g*, and through ducts *h'''*, with the chamber *b''*, surrounding the direct feed *a*, *a''*. It also communicates through the ducts *h''''*, with the ajutage chamber *d'*.

The direct feed conduit *c*, considered as a whole, is adjustable longitudinally on and in the body portion *b*, by means of the screw thread *c''''*, by which it engages with the said body portion *b*. This adjustment or removability, for the purpose of introduc-

ing the spiral c^7 , may be effected by means of the collar or flange c^3 , before the application of the supply conduit a , a^2 , a^3 , or the latter may be removed temporarily for the purpose, the object being to regulate the conical valve c^5 , with accuracy with relation to the valve port d^2 , in the head member d , to control the flow of vapor from the valve chamber f , to the ajutage chamber d' . This supply is checked by the disk valve i , slidable on the spout c^6 , a spring i' , being interposed between said disk valve i , and a shoulder c^{66} , on said spout c^6 , so that normally the supply of vapor from the valve chamber f , is cut off and remains so until the suction in the mixing chamber e , and ajutage chamber d' , is sufficient to lift the disk valve i , against the resistance of the spring i' . The valve cone c^6 is adjusted with relation to the port d^2 by turning and screwing the member c up or down, the part c' moving with the member c , as will be obvious from an inspection of Fig. 1. The helical passage c^7 connects the feed chamber a^2 with the valve chamber f , as is also evident from Fig. 1.

The cap e' , extends down around the upper portion of the body portion b , like an apron and is secured thereto by screws e^2 , or otherwise, but in any case passages e^3 , are formed between it and said body portion b , which passages open communication between the atmosphere and the annular space k , closed at top by an annular cap k' , which is perforated to control the injection of air into the mixing chamber e . A pipe m , connects the annular space k , with a source of moisture, as for instance the water vaporizer M , consisting of a cylindrical air chamber m' , into which water is injected by any suitable means, as by gravity through a spout n , connected by pipe n' , with a water tank N ,—a valve n^2 , being interposed in the pipe n' , to regulate the flow. The nozzle n , is surrounded by an inverted conical cup or shell m^2 , which acts as a retarding reservoir for the water which escapes therefrom through the central opening m^3 , immediately above the spout n . Air is admitted to the chamber m' , through ports m^4 , the area of which may be regulated by sliding the telescopic cylinders m^5 , m^6 , constituting the sides of the chamber m' , one upon the other, as will be readily understood by reference to Fig. 2. The end of the moisture pipe m , within the vapor chamber m' , is preferably provided with an inverted funnel m'' , and the pipe is boxed at its connection with the vaporizer M , so that it and the funnel m'' , may be adjusted toward or from the spout n , and reservoir m^2 , for the purpose of regulating the area of the air space into which the water is injected.

In lieu of water from the tank N , which may be shut off entirely when desired by means of the valve n^3 , a decarbonizing liquid may be substituted, derived from the tank P , and controlled by the valve p . The suction of the engine draws in warm air through the flue h as well as external air through the passages e^5 . It is to be understood that there are no injections of any kind, but only suction. Hot air will be drawn into the chamber g through the passage h^3 . The exhaust passes off through the passage h^4 , incidentally heating the air in the purifier h^2 to be delivered to the jacket h through the passage or flue h^1 .

I intend to use a constant level fuel chamber communicating with the pipe a so that the fuel in the chamber g is maintained at a definite, constant level, as shown in Fig. 4.

The hot air circulating through the jacket H , ducts h^3 , h^4 , h^5 , and the chamber b^2 , tends constantly to maintain the temperature of the feed nozzle A , at a sufficiently high degree to facilitate the flow and vaporization of the liquid hydro-carbon and prevent carbonization and "coking". The two tubes c , c' move together when the tube c is adjusted on the screw c^4 to regulate the cap k' with relation to its conical seat.

At low motor speed the supply of hydro-carbon delivered directly through the axial feed conduit c^6 , is sufficient. As the speed increases the suction exerted in the mixing chamber e , and ajutage chamber d' , raises the valve i , against the resistance of its spring i' , drawing an auxiliary supply of hydro-carbon vapor from the valve chamber f , which derives its supply from the reserve chamber g , and also from the feed chamber a^2 , through the medium of the spiral duct c^7 .

Atmospheric and moist air admitted through the ducts e^4 , k , k' , k^2 , and h^4 , increase the supply of oxygen and insures perfect combustion of fuel, thereby preventing carbonization, since only gaseous products result from the ignition of the thorough admixture of hydro-carbon vapor, air, and moisture.

The longitudinal adjustment of the direct feed conduit c , enables me to regulate the admission of the auxiliary supply of fuel through the high speed port d^2 , with accuracy, according to the conditions and requirements of use; and the automatic check valve i , prevents an over supply of fuel when the motor is working at low speed.

I have found by experimental investigation that moist atmosphere or moistened air, introduced into the hydro-carbon charge tends to insure more perfect combustion, resulting in the attainment of the full efficiency of both fuel and motor, which latter consequently runs more smoothly and evenly, avoiding the deleterious effects of carbon.

zation or "coking". Hence my provision of means for the introduction of moisture-laden air into the nozzle A, is an important feature of the invention.

5 In practice, the nozzle is connected at the bottom with a gasoline supply tank, and is so arranged as to inject into the "Venturi tube" leading to the throttle.

What I claim as my invention and desire to secure by Letters Patent is,

1. In a nozzle provided with an inlet for the supply of hydrocarbon, a direct feed chamber, an axially disposed direct feed fuel conduit, means including passages for 15 heated air surrounding the nozzle for vaporizing the hydrocarbon, and passages within the nozzle for heating all parts thereof, and means for inducing moist air at atmospheric pressure into the vaporized hydrocarbon.

2. A nozzle having auxiliary and main chambers and a mixing chamber at the end with a port at its inner end, a longitudinally adjustable axial hydrocarbon feed conduit 25 controlling said port, in direct communication with the main feed chamber and formed with a conical portion for regulating the area of the port through which an auxiliary supply of hydrocarbon may be admitted to 30 the mixing chamber, and means within the nozzle whereby a circulation of hot air through the body of the nozzle may be effected, said chambers being connected by ports extending lengthwise of the nozzle.

3. A nozzle having auxiliary and main chambers and a mixing chamber at the end with a port at its inner end, a longitudinally adjustable axial hydrocarbon feed conduit 40 controlling said port in direct communication with the main feed chamber and formed with a conical portion for regulating the area of the port through which an auxiliary supply of hydrocarbon may be admitted to 45 the mixing chamber, means within the nozzle whereby a circulation of hot air through the body of the nozzle may be effected, said chambers being connected by ports extending lengthwise of the nozzle, and a valve 50 for controlling the auxiliary supply of hydrocarbon.

4. A nozzle having a mixing and a fuel chamber, means including longitudinally disposed ducts within said nozzle for effecting a supply of hydrocarbon to the mixing 55 chamber through an auxiliary high speed supply chamber, an auxiliary high speed supply chamber, a helical duct leading from the fuel chamber for inducing a jet of hydrocarbon into a chamber adjacent the outer 60 end of the nozzle, said nozzle being formed with ports affording communication between said fuel, auxiliary high speed supply and mixing chambers.

5. A nozzle having means including ducts 65 within the nozzle for inducing air at atmos-

pheric pressure into the vaporized hydrocarbon, means for vaporizing such hydrocarbon, a mixing chamber at the outer end of the nozzle, a main fuel feed supply chamber, an auxiliary fuel supply chamber for 70 high speed, an axial main feed conduit, and ducts affording communication between the auxiliary high speed supply chamber and a valve-controlled chamber at the outer end of the nozzle.

6. A nozzle having means including ducts within the nozzle for inducing air at atmospheric pressure into the vaporized hydrocarbon, means for vaporizing such hydrocarbon embodying a mixing chamber at the outer end of the nozzle, a main fuel feed supply chamber, an auxiliary fuel supply chamber for high speed, an axial main feed conduit, ducts affording communication between the auxiliary high speed supply chamber and a valve-controlled chamber at the outer end of the nozzle, and a helical duct leading from the fuel chamber for inducing a jet of hydrocarbon into a chamber adjacent said valve chamber.

7. A nozzle of the character designated formed with a mixing chamber at one end, an axial fuel supply for the same at low speed, an auxiliary fuel supply for high speed, a suction valve controlling the supply 95 from said auxiliary fuel supply to the mixing chamber, said chambers being disposed at the longitudinal axis of the nozzle adjacent opposite ends thereof and through which the axial fuel supply extends.

8. A nozzle of the character designated formed with a mixing chamber at one end, an axial fuel supply for the same at low speed, an auxiliary fuel supply for high speed, a suction valve controlling the supply 105 from said auxiliary fuel supply to the mixing chamber, said chambers being coaxially disposed adjacent opposite ends of the nozzle and through which the axial fuel supply extends, and means for adjusting the 110 area of the exit port of the auxiliary supply chamber.

9. A nozzle comprising an inlet for the supply of liquid hydrocarbon at one end thereof, a direct feed chamber, and a direct feed conduit extending within said chamber, said feed conduit comprising a central tube and a tubular jacket secured thereto with a helical duct between said tube and jacket and communicating with the axial 115 feed chamber at one end and with a valve chamber near the other end of the nozzle, said nozzle being formed with a hydrocarbon reserve chamber in communication with said valve chamber.

10. A nozzle comprising an inlet for the supply of liquid hydrocarbon at one end thereof, a direct feed chamber, and a direct feed conduit extending within said chamber, said feed conduit comprising a central tube 120

and a tubular jacket secured thereto with a helical duct between said tube and jacket and communicating with the axial feed chamber at one end and with a valve chamber near the other end of the nozzle, said nozzle being formed with a hydrocarbon reserve chamber in communication with said

valve chamber, and a jacket surrounding the body portion of the nozzle and communicating with said reserve chamber:
